Inventor,
Harry Jones

By J. P. Livermore

UNITED STATES PATENT OFFICE.

HARRY JONES, OF SUFFERN, NEW YORK, ASSIGNOR TO AMERICAN BRAKE SHOE & FOUNDRY COMPANY, OF MAHWAH, NEW JERSEY, A CORPORATION OF NEW JERSEY.

BRAKE-SHOE.

1,313,540.

Specification of Letters Patent.

Patented Aug. 19, 1919.

Application filed March 8, 1919. Serial No. 281,449.

To all whom it may concern:

Be it known that I, HARRY JONES, a citizen of the United States, and a resident of Suffern, in the county of Rockland and State of New York, have invented an Improvement in Brake-Shoes, of which the following description, in connection with the accompanying drawings, is a specification, like reference characters on the drawings representing like parts.

This invention relates to brake shoes and consists mainly in a novel construction of an insert of hard material, embedded in the main casting of a brake shoe to increase the effectiveness and serviceability of the brake shoe.

In Patent No. 1202529 granted October 24, 1916, I have shown a brake shoe provided with an insert composed of a hard wear-resisting material in open-work form, having incorporated in it a core of ductile material, and the present invention may be regarded as an improvement upon the construction forming the subject of that patent.

As shown in said patent the ductile core was embedded in a hard iron alloy and was incorporated in the insert by dipping a suitably open-work formed of foraminous core into the hard material while in molten condition, which resulted in forming a coating of the hard material on the core.

Such procedure is attended with some difficulties especially in making the larger sizes, which difficulties are avoided in the construction forming the subject of the present invention.

Furthermore the sectional shape of the insert when formed by dipping is such that after the brake shoe and insert have been reduced to a certain extent by wear, the portion of the insert that remains embedded in the softer material of the brake shoe is not interlocked therewith and is liable to be dislodged or broken away, leaving cavities in the face of the brake shoe, an effect which is detrimental.

This is owing to the fact that the adhesion between the metal of the insert and the metal cast upon it is not very great, and the objectionable result is obviated in the insert forming the subject of the present invention by making the same of such sectional shape that it remains interlocked with

the material of the shoe until the material of the insert is substantially entirely worn away.

The term dovetail will be used to designate this sectional formation of the insert, it being intended that the term shall be understood as including any form in which the cross sectional shape of the embedded portion of the insert increases in width as it increases in depth or distance from working face of the shoe, so that the material of the shoe over-hangs and engages positively with the material of the insert until the latter is substantially entirely worn away.

The insert forming the subject of the present invention having the general foraminous or open-work form and the dovetail sectional shape above indicated, is cast in a mold, the cavity of which contains the foraminous ductile core member, which thus becomes surrounded by and embedded in the casting made from the hard wear-resisting material, which casting is thereafter incorporated in the brake shoe in the usual manner by placing it in a suitable mold cavity and running in the cast iron of which the main portion of the brake shoe body is made.

Figure 1 is an elevation of the working face of a brake shoe, provided with an insert, embodying this invention;

Fig. 2 is a similar view of the insert as it appears before being incorporated in the brake shoe, said insert being shown partly in section to show the core of ductile material;

Fig. 3 is a cross sectional view on lines x^3 , Fig. 1; and Fig. 4, is a cross sectional view on line x^4 , Fig. 2.

As shown in Fig. 1, the insert 2, is foraminous, or of open-work formation, being composed of portions that intersect preferably at the acute angle shown, the general formation being practically like that of what is now known as expanded metal.

This specific form of the foraminous or open-work insert is not essential, although it is desirable because of its similarity to that of expanded metal, one or more pieces of which may be employed to constitute the ductile core 3 of the insert.

When expanded metal is used for the due-

tile core of the insert, one or more strips of the expanded metal are placed in the cavity of a suitable mold, and the molten material forming the main body of the insert is 5 poured into the mold, the result being that the ductile core is incorporated in the insert throughout the intersecting bars, or parts of which the open-work insert is made up.

The material of which the main body of 10 the insert is composed, may be any suitable hard wear-resisting material, such as iron alloys containing various proportions of carbon in solution, and various other ingredients, making a metal such as is variously 15 known in shop parlance as hard steel, or crucible steel, or white iron; or chilling cast iron, such iron alloys having been found satisfactory in practical service.

Referring to the figures of the drawing 20 which show the sectional shape of the insert, it will be seen that the insert is of a general tapering form, being of less thickness at the wearing face 4 of the brake shoe than at the surface which lies at the greatest depth from said face in the body of the 25 brake shoe.

This tapering or dovetail formation facilitates the drawing of the pattern for the 30 insert from the mold and also causes the insert to interlock with the material of the main body of the brake shoe, the interlocking or dovetail engagement of the insert in the body of the brake shoe remaining until the insert and material of the shoe at the 35 sides of the insert are entirely worn away.

The open work formation of the insert has practically the same advantages as were 40 pointed out for the sinuous insert shown in my prior Patent No. 995012, dated June 13, 1911, and as that of the hard metal insert shown in my prior Patent No. 1202529, hereinbefore referred to, but the cast or molded insert forming the subject of the present 45 invention affords a better distribution of the hard material in the body of the brake shoe and a more effective interlocking of the insert material with the body of the brake shoe, than does the construction shown in said Patent No. 1202529 and is less costly 50 in the labor required for its production.

The present construction also affords a larger proportion of the hard material relative to the ductile core material than is readily attainable in the construction shown 55 in said earlier patent.

The brake shoe is completed by placing as many as may be found desirable of the inserts in the cavity of the brake shoe mold,

and casting the remainder of the body portion 5 of the brake shoe around the same. 60

By having the intersecting bars or portions of the foraminous or open-work insert disposed diagonally in the brake shoe body as represented it will be seen that the wearing face of the shoe presents alternating 65 portions of the hard and soft material in the line of frictional movement of the wheel tread along the face of the shoe, throughout the width of the same, which is found to be effective for affording a high frictional 70 coefficient, and also for producing a more uniform wearing action upon the frictional surfaces than is the case when the hard and softer portions are less equally distributed throughout the wearing face of the shoe, and 75 especially when the hard portion extends uninterrupted for a considerable distance in the direction of the movement of the wheel tread.

It is not essential that the core of ductile 80 material should be a unitary piece of expanded metal, although that is an exceptionally convenient construction for introducing the strands of ductile core material into the mold in which the insert is cast. 85 The core material may be merely laid in the cavity of the mold in which the insert is cast and will be more or less floated in the casting operation, so as to become completely 90 surrounded and inclosed by the hard material of the insert as shown in the drawings.

While a single piece or strip of the core material is shown and has been found to be sufficient for the performance of its function in connection with the harder but more 95 brittle material of the insert, there is no limitation to any definite number of lines or strands of the core material incorporated in the hard material of the insert.

What I claim is:

1. A brake shoe insert composed of a foraminous or open work casting of hard wear-resisting iron alloy having a core of ductile material incorporated and inclosed therein, said insert being of dovetail sectional shape substantially as and for the purpose described. 100

2. A brake shoe comprising a cast metal body having embedded therein a cast metal insert composed of a foraminous casting of hard wear-resisting material of dovetail sectional shape, having inclosed within it a core of ductile material. 110

In testimony whereof I have signed my name to this specification.

HARRY JONES.
